UNITED STATES PATENT OFFICE.

ALEXANDER HAHN, OF NEW YORK, N. Y.

FOLDING TABLE.

1,289,739.

Specification of Letters Patent. Patented Dec. 31, 1918.

Application filed September 23, 1916. Serial No. 121,702.

To all whom it may concern:

Be it known that I, ALEXANDER HAHN, a citizen of the United States of America, residing in the borough of Manhattan, city, county, and State of New York, have invented certain new and useful Improvements in Folding Tables, of which the following is a specification.

This invention relates to folding furniture, and particularly tables, such as are frequently used for card tables, and so designated in the trade. The object of the invention is to provide a strong and durable table of light construction, and one which can be placed upon the market and retailed at a moderate price; also, to provide a table which can be safely and economically shipped by parcels post, and one which can be readily carried about by hand for use.

20 The various structural features can best be pointed out when describing the invention in connection with the drawings.

The drawings accompanying this application illustrate one form of practicable embodiment of the invention as applied to a card table of light weight construction, in which drawings,—

Figure 1 is a top view of a table equipped with my invention, partly broken away and 30 partly shown in horizontal section, one of the legs being represented in its open position and the other legs closed;

Fig. 2 is a section of Fig. 1 taken at about the plane of the line 2—2. The line 1—1 in 35 Fig. 2 indicates the plane of the section of Fig. 1; and

Fig. 3 is a detail of the plane of a section of Fig. 2 showing a leg in a different position.

40 The illustrated table is shown as having a square top and four foldable legs. The top 5 in the present illustration is assumed to be some flexible or yielding material, such as fiber board. The edges of the top material 45 are shown bent over and secured between a dependent framing member 6 and an outer finishing strip 7. This frame in part supports the top, but this, when made of thin material for economy and lightness, requires

50 a certain amount of bracing, which is afforded in the present illustration by a swastika-shaped truss comprising two cross bars or members 8 secured to the under side of the top and crossing at the center thereof. 55 The outer or transverse arms of the swastika-shaped frame are designated by

the reference characters 9, and are also secured to the under side of the table top and disposed parallel with the adjacent framing member 6. The space between the members 60 9 and 6 accommodates a portion of the leg 10 and its locking brace 11. The leg is shown so pivoted that it may be extended for the purpose of supporting the table, as illustrated in Fig. 2, or folded against the 65 under side of the table top for transportation and storage, as illustrated in Fig. 3. The pivot is represented as a common wood screw 12, passing through the top of the leg and into 70 the frame member 6. Suitable spacers 13 are illustrated at the sides of the leg.

The brace 11 for holding the legs securely in their extended position and for holding them in their folded position comprises a 75 spring wire bent at its center and held to the leg at a suitable distance from the pivoted end by means of a bearing plate 14. The side wires are shown provided with transversely outwardly extending bent ends 80 or lugs 15 which respectively ride in grooves 16 cut in the opposing faces of the members 9 and 6. Each of these members is provided with a recess, in the present instance merely a bored hole, 17, for receiving the 85 bent-over ends 15 when the leg assumes its full open position, in the present illustration perpendicular to the plane of the table top.

The elasticity of the brace 11 is relied 90 upon to hold the ends 15 in the groove. When it is desired to close the leg the operator grasps both of the wires with his hand and squeezes the ends toward each other. In ordinary practice considerable care 95 would have to be exercised to squeeze both wires equally and not flex either sufficiently to withdraw it from the slot 16 at the time it is withdrawn from the recess 17. To guard against this a back stop 18 is provided between the recesses 17, so that the operator may readily take hold of both wires and flex them until they are arrested by the stop, whereupon the leg may then be moved to position.

When it is desired to open the table the operator preferably puts it in substantially the position it occupies in Fig. 1, having the legs away from him and the top 5 toward him. He will thereupon take each leg in 110 turn and move it to its open position. Upon the lugs 15 arriving at the recesses 17 they

snap into place and securely hold the leg in position. When it is desired to close the table the operator preferably turns it up in a similar position and grasps the wires with his hand, squeezing them together against the back stop 18 and at the same time forcing the leg to its closed position, in which it is held by the frictional engagement of the ends of the lugs with the bottom of the groove 16. The back stop 18 is preferably made of such height that its face serves to limit the inward movement of the leg.

The pivot screw 12 acts to securely connect the free end of the transverse member 9 of the swastika frame with the frame member 6 of the table top. The outer ends of the center or crossed members 8 abut against the inner side faces of the adjacent transverse members 9 of the swastika, and such members 8 receive in a longitudinal direction pressure applied to the outer side faces of the transverse members 9 by the spring action of the brace member 11. Such spring action would have a tendency to displace the member 9 were this not in close engagement with the center member 8. A table of this character is frequently in a closed position for longer periods than it is in an open position, and the above described structure adds greatly to the lasting qualities of the table. When the table is in an open position the brace engages the member 9 about midway between the point at which such brace receives support from the member 8 and the pivot screw 12. This feature also adds to the enduring qualities of the table.

What I claim is:—

1. In a folding table, the combination with a table top having at its underside a rectangular outer frame and an inner frame

having side members disposed parallel with but spaced apart from the said outer frame and leaving a free space surrounding the inner frame, and a leg pivotally connected to the table top between the inner and the outer frame members at each side adjacent one end of the side member of the inner frame and adapted to fold along such side into the said free space and when so folded extending beyond the other end of such side, each leg being located in such relation to the inner frame as to afford a space for the free end of the adjacent leg when this is folded. 45 50

2. In a folding table, the combination with a table top having at its edge a dependent frame, a swastika-shaped truss secured to the under side of said table top and having its transverse members disposed parallel with, but spaced apart from the said dependent frame, a leg pivoted between the free end of the said transverse member and the adjacent dependent frame member, and a brace pivoted to the leg and comprising a pair of spring arms, there being grooves in the opposing faces of the frame and truss 65 members, and the ends of said arms being bent outwardly for traversing the said grooves, and recesses in said grooves for receiving the said outward extensions and holding the leg in its open position, the 70 arms of the brace being of such relative proportions that upon the leg assuming its closed position the free ends of the brace assume a position in substantial alinement with the crossed members of the swastika 75 frame.

In witness whereof, I have hereunto signed my name this 22 day of September, 1916.

ALEXANDER HAHN.
